G. M. JOHNSON

Des. 169,041

COMBINED PLAYING CARD HOLDER, ASH TRAY, AND GLASS COASTER

Filed May 20, 1952

FIG. 2.

INVENTOR
Gladys M. Johnson

BY

Oliver D. Olson

AGENT

UNITED STATES PATENT OFFICE

169,041

COMBINED PLAYING CARD HOLDER, ASH
TRAY, AND GLASS COASTER

Gladys M. Johnson, Timber, Oreg.

Application May 20, 1952, Serial No. 19,794

Term of patent 14 years

(Cl. D34—13)

To all whom it may concern:

Be it known that I, Gladys M. Johnson, a citizen of the United States, residing at Timber, county of Washington, State of Oregon, have invented a new, original, and ornamental Design for a Combined Playing Card Holder, Ash Tray, and Glass Coaster, of which the following is a specification, reference being had to the accompanying drawing, forming a part thereof, in which:

Figure 1 is a perspective view of a combined playing card holder, ash tray, and glass coaster showing my new design; and

Figure 2 is a sectional view taken along the line 2—2 in Figure 1.

I claim:

The ornamental design for a combined playing card holder, ash tray, and glass coaster, as shown.

GLADYS M. JOHNSON.
